UNITED STATES PATENT OFFICE

VICTOR PETTERSON, OF CHICAGO, ILLINOIS

TIME-CONTROLLED SWITCH

Application filed October 24, 1928. Serial No. 314,633.

The present invention has to do with a circuit employed in coin controlled radio sets and relates particularly to a means for discouraging efforts to render the coin control ineffective.

With the use of a coin controlled apparatus, the owner of the apparatus invariably finds the results of the depredations of a certain class of individuals who interfere 10 with the coin control for the purpose of "beating the machine."

Many persons, otherwise honest, are inclined to use their most agile thoughts to defeat the purpose of the coin control.

Approached from a psychological point of view, the most efficient means for terminating such improper efforts is to penalize the tamperer and take away the benefits of the device, or to make it appear such tampering has broken the apparatus. None other than an actual thief ordinarily will tamper with an apparatus after the effect of his efforts tends to make him believe that he is destroying, breaking, or disarranging such 25 apparatus.

It is with these ideas in mind that the present combination of elements was devised, and from the foregoing discussion, it will be apparent that the invention relates to a 30 radio apparatus intended for hotels, amusement parlors, and elsewhere where the machine may be located for the operation of the public subject only to the necessity for placing a coin therein prior to rendering the 35 device operative.

In such a device, it is necessary to provide a coin detector which is used in conjunction with the radio apparatus itself, and there must be such association between the 40 coin detector and its parts and the radio circuit that the radio apparatus can not be worked until the coin apparatus shall have been properly actuated. Further, there must be a time determining element, such as a 45 clock mechanism or the equivalent thereof, to regulate the period over which the radio circuit is closed upon actuation of the coin detector mechanism. In order to carry out the objects of the invention hereinafter re- 50 cited, it is necessary to break the radio cir-

cuit coincidentally with any improper manipulation in respect to the coin detector.

Included in the objects of the invention, therefore, are the provision of the following:

A coin detector in association with a radio circuit adapted to break the radio circuit as an incident to improper manipulation of such coin detector;

A novel mechanism adapted to be controlled by a coin and comprising a coin detector, a time limiting element, and a radio circuit which is broken independently of the time controlling element when improper manipulation of the coin detector is had;

A new method of breaking a radio circuit through the employment of a coin controlled radio apparatus;

An unique apparatus comprising a coin detector, a time fixing element, and a radio circuit, and in which there are means for breaking the radio circuit as an incident to improper actuation of the coin detector;

Improved means for breaking a circuit in a radio circuit actuated by a coin controlled element;

The provision, in combination with a clock mechanism, of a switch mechanism actuated thereby having novel clock stopping means; and

The provision of novel mechanism for definitely controlling the period of time over which a clock mechanism controlling the activities of other elements may operate.

These, and such other objects as may hereinafter appear, are obtained by the novel construction, combination, and arrangement of the several elements which constitute the invention.

One embodiment only of the invention is disclosed, and this is illustrated in the accompanying two sheets of drawing, hereby made a part of this application, and in which:

Figure 1 is a perspective view of a radio 95 cabinet containing a radio set and having the coin controlling mechanism therefor disposed in one end;

Figure 2 is a rear elevation of the coin controlling mechanism shown in Figure 1, the 100

cover therefor being removed, the section being along the line 2—2 of Figure 6;

Figure 3 is a longitudinal section along the line 3—3 of Figure 7;

5 Figure 4 is a fragmentary vertical section along the line 4—4 of Figure 6 and is illustrative of the means employed for actuating the main switch for radio circuit controlled by the clock mechanism illustrated in Figures 10 2, 3, 6, 7 and 8, one position shown being when the switch is open and the other when the switch is closed;

15 Figure 5 is a fragmentary vertical section along the line 5—5 of Figure 6 and is a detailed view of the main switch member of the radio circuit controlled by the clock mechanism hereinabove referred to, the switch in open position being shown in full lines and in closed position being in dotted lines;

20 Figure 6 is a vertical transverse section along the line 6—6 of Figure 3 and looking in the direction of the arrows;

25 Figure 7 is a similar sectional view along the line 7—7 of Figure 3 and looking in the direction of the arrows;

Figure 8 is a fragmentary top sectional view taken along the line 8—8 of Figure 2 and looking in the direction of the arrows;

30 Figure 9 is a vertical section along the line 9—9 of Figure 8 and discloses the inner mechanisms of a coin detector such as is illustrated in Figure 1, other coin detectors being adapted to serve in the present apparatus with equal facility;

35 Figure 10 is an elevation of the parts shown in section in Figure 11, the cover of the apparatus having been broken away for clarifying the view, the full lines showing the parts when the coin detector is in its normal position and the dotted lines its extreme position when winding the clock mechanism and closing the main radio circuit;

40 Figure 11 is a vertical transverse section along the lines 11—11 of Figure 10; and

45 Figure 12 is a front elevation of the coin detector, two of which are shown in Figure 1.

Like reference characters are used to indicate similar parts in the drawing and in the following specification.

50 Reference should be had first to Figure 1. For purposes of indicating the application of the present invention to a conventional radio set, a perspective view of a commercially well-known radio set having the present invention applied thereto is shown. In such illustration, the cabinet is indicated by the numeral 20, the tuning handle or control by the numeral 21, the compensator by the numeral 22, and the volume control handle by the numeral 25. The open dial for reading the wave lengths and through which in most sets a scale upon which a light is visible, is indicated by 24.

55 The cabinet 20 is so made that access thereto may be had only by key, there being a

lock arranged in association with the cabinet 20 whereby the cabinet is closed against thieves and the inquisitive. The cabinet may be of any suitable material but preferably is of metal. Any suitable lock may be employed on said cabinet 20, none being shown, and the device may open at the top, the back, or the bottom, as is preferred.

60 In an end panel 26 of the cabinet 20 the mechanism forming the subject matter of the present invention is installed. For convenience, the present invention will be called the timing element and will be designated generally by the numeral 27. The invention may be manufactured as a unit capable of installation in any selected radio set.

65 In order to meet the demand for the use of a device of this character and to satisfy the demands of the greatest possible number of customers, it has been found desirable to 85 employ two coin actuated control mechanisms 28 and 29, one of which is adapted to be actuated by a nickel or dime and permitting of a five or ten minute operation of the device, and the other actuated by a quarter 90 and permitting of a half hour's use of the apparatus. These coin detectors are mounted side by side upon a panel 30, such panel adapted to be inserted into and firmly secured in an opening provided therefor in 95 the cabinet end 26.

70 Said panel 30 includes a plurality of fastening members 31 which, in the present instance are screws welded to the back of the panel 30 so that there will be no possibility 100 of removing the panel 30 through the agency of its fastening means from the end 26 and the outside of cabinet 20.

75 At each end of the panel 30 are angle irons 32 which may be welded into proper position and which provide guide members for the frictional engagement thereon of a cover 33. The cover 33 comprises a top 34, a back 35, ends 36 and 37, and an abbreviated bottom section 38. Such member 33 provides a 110 shield for the whole mechanism disposed upon panel 30 and is effective for preventing the insertion, through the coin detectors or either of them, of a wire or other element which might possibly attain contact with 115 the radio circuit which is disposed to one side thereof, the radio circuit being to the right of the portion 35 shown in Figure 6.

80 The abbreviated bottom section 38 is necessary in order that coins passing through the detectors 28 and 29 may drop out of the mechanism into any suitable receptacle which may be placed beneath the opening intermediate the panel 30 and the back portion 38. No such receptacle is shown for it forms 125 no part of the subject matter of the invention.

85 Mounted in the back 35 is a suitable socket 39 into which may be inserted a plug 40, the socket 39 being of any approved type whereby 130

the plug normally employed may be attached thereto. The current fed into and out of the present apparatus may be the normal light socket current with which most radio sets are now energized and the circuits herein described comprise one having two switches which are controlled by the present mechanism, one which is normally open and adapted to be closed by actuation of either of the clock mechanisms associated with the coin detectors 28 or 29, and the other which is normally closed and which is opened each time there is a movement of either of the handles of the coin detectors 28 or 29 as will hereinafter be pointed out.

A radio circuit is neither illustrated nor described as this appears unnecessary. One side of the socket 40 may lead to a source of energy and the other side to the radio circuit employed and through said radio circuit to the other side of the source of energy.

As the mechanisms with which the coin detectors 28 and 29 are associated are identical in structure and in their employment in the present apparatus except that one takes a longer period of time to operate, only one thereof will be described fully. This will prevent the duplication of description. It will of course be understood in advance that the circuits hereinafter mentioned are so arranged that either coin controlled members 28 or 29 may close the circuit entering through the conduits carried by the plug 40 to the radio circuit, one for a short period of time and the other for a longer period of time, but that such circuit will be broken by manipulation of the handle of either of the coin detectors 28 or 29.

From one of the conduits carried by the plug 40, a short cable 41 is energized. This cable 41 is suitably connected to a spring stationary contact 42 which is disposed upon a bracket 43 upon panel 30. Said contact 42 is insulated from bracket 43 by sheets of insulation 45 and 46. A second bracket 47 is suitably affixed to the plate 30, and this is for use in association with the second coin detector mechanism. An ancillary short cable 48 is disposed so as to energize a second contact 42 of the same nature and actuated in the same manner as the contact 42 disposed upon the bracket 43.

Each of contacts 42 is fixed, as indicated, and is adapted to be impinged by movable spring contact 49, each of which has a V-shaped hump 50 which normally engages the tip of fixed contact 42. The spring in said contacts 49 is such that it urges separation of contacts 49 and 42, and in order to maintain contact therebetween, it is necessary to provide a positive means to counteract the urge of the spring tension.

Contacts 49 have an elbowed supporting section 51 which is secured upon an angle iron 52 anchored upon a second angle iron

58, the latter being suitably attached to the panel 30, the angle irons 53 and 52 conjointly providing a housing beneath which certain of the mechanism hereinafter described is disposed. At the rear thereof, they support a clock mechanism hereinafter also to be described.

The elbowed section 51 of contact 49 is insulated from the angle iron 52 by sheets of insulation 54 and 55, or by any other suitable insulatory means. Similar construction will be found at both the right and left hand sides of Figure 2.

From the elbowed section 51 there is a cable 56 which extends to a switch member or circuit breaker controlled by the clock mechanism. Said cable 56 is connected to a fixed contact 57 in said circuit breaker which contact is mounted upon fiber. There is at one end of the contact 57 an extension portion 58 to which the cable 56 is electrically connected and at its other end is an offset portion 59 where electric contact with a movable member is made.

Said member 57 is mounted upon, as indicated above, a fiber sheet (which is indicated as 60) and upon such sheet 60 and opposed to and in reverse position to the contact 57 is a second contact 61 having an extension 62 to which a conducting cable is attached. Said contact 61 has an offset portion 63 for the engagement of a movable contact 64 which movable contact is pivoted at 65 and is provided with a spring 66. Member 64 is adapted to bridge contacts 57 and 61 to establish electrical connection therebetween.

The radio set in association with the device is adapted to operate only, of course, when there is electrical contact between the movable contact 64 and the offset portions 59 and 63 of the fixed contacts 57 and 61. From the extension portion 62 of the left hand mechanism shown in Figure 2, there is a cable 67 which extends to the contact 61 on the right hand section or part of the apparatus from which latter contact 61 there is a cable 68 to the opposite side of the socket 39 and which completes the energizing circuit to the radio set when the plug 40 is inserted in the socket 39, provided the switch including members 57, 61 and 64 is closed.

The fiber block 60 is securely disposed, by the use of reduced ends which engage in slots upon a U-shaped member 69 and is adapted to close the open section thereof. Said U-shaped member is firmly secured to a bracket 70 which might be integral but which is illustrated as comprising an angle iron 71 secured upon a second angle iron 72, the latter being suitably attached to the panel 30. As is clear from Figure 6, the contact 64 and its pivotal mounting 65 are insulated from the contacts 57 and 61, and also that the movable contact 64 is insulated from all

other parts of the device, except when the circuit breaker is in closed position when said contact 64 engages contacts 57 and 61.

For the actuation of the said movable contact 64, it is necessary that the clock mechanism shortly to be referred to be partially wound. Intermediate the clock mechanism, which is in part mounted upon the bracket 70, and the movable switch 64, is the coil 10 spring 66 which is anchored at one end upon a fiber disc 73, shown in Figure 4, and at its other end upon a prong at the upper end of said movable contact 64. The clock mechanism which actuates the disc 73 is so disposed that so long as it is actuating and the radio circuit is closed for the period provided for by the amount of money paid by the user through detectors 28 and 29 there will be a tension upon the contact 64 whereby it will 15 be held in physical and electrical contact with the offset portions 59 and 63 of fixed contacts 57 and 61, but at the instant of expiry of the period for which the user has paid, the disc 73 upon which the spring 66 is 20 anchored will have been moved by the clock mechanism to a position where such tension shall have closed and the tension has become such that it urges the contact 64 to disengage itself from contacts 57 and 61. The instant that the dead center of the contact 64 25 intermediate and influenced by the two tensions referred to shall have been passed, the tension upon the spring 66 will break the circuit, the break in circuit being of an instant nature. The parts will be moved by the actuation of the spring 66 from the dotted line position shown in Figure 5 to the full line position shown in the same figure, thus opening the circuit to the radio receiving device. This will be a quick break and 30 prevent arcing in the set which might occur in the event the contacts were slow to separate.

The position of the spring member 66 45 upon the disc 73 where it is anchored by a peg 74 which is firmly secured in the fiber material of the disc necessarily determines the period of time over which the circuit may be closed by the switch fully illustrated and 50 described in Figures 4 and 5, and hereinabove described.

By reference to Figure 4 which is a detail of such disc which is controlled by the clock mechanism it will be instantly apparent just 55 what movements the disc 73 makes from the position attained as an incident to operating one of the coin controlled members 28 or 29 to the time that the circuit is broken by the clock mechanism running down to a limited 60 extent.

To actuate said disc 73 there must first be deposited in the coin detector 28 or 29 the proper coin. The handle 75 of the coin detectors 28 or 29 is then moved in a clockwise 65 direction. Mounted upon the coin detector

is a drum 76 best shown in Figure 11. About this drum and anchored thereon is a coil spring 77, the other end of which spring may be anchored upon the member 72. Movement of the handle 75 of the coin detector, which movement of course causes the remainder of the parts thereof to be actuated, increases the tension upon the spring 77 so that at the instant the handle 75 is released the coin detector is urgently returned to its normal 70 position, a fixed position which it continues to occupy unless someone manually moves it again in a clockwise direction. In such fixed position contacts 42 and 49 are in engagement.

In addition to the drum 76, just referred to, there is a second drum 78 which has at one side thereof an extension or lug 79. Upon such extension is a stud or a roller bearing 80 which bearing is adapted to impinge spring contact 49. For purposes of insulation, the member 49 is supplied with an insulating back or sheet 81 which is tied or fastened thereon by means shown at 82. Thus electrical connection between the member 49 and the coin detector is prevented. 80

So long as the coin detectors 28 or 29 are in their normal position the stud 80 impinges the insulatory material 81 and urges the hump 50 of the contact 49 into engagement with the spring contact 42, but the instant that the handle 75 is moved in a clockwise direction, the elbowed spring portion 51 causes an instant disconnection whereby the circuit hereinabove referred to, if closed, is broken. Thus, when anyone tampers with the handle 70 by moving it from a position away from that at which it normally rests, the circuit to the radio receiving set will be broken during the operation of said set as 95 an incident to the payment of the price for such use.

The instant effect of such movement is to cut off the electromotive force by which the radio receiving set is operated and the music or speaking voice which is being heard thereon is stilled. The psychological effect of the breaking of the circuit and the stilling of the radio receiving set generally is such that the person who has manipulated the handle 100 75, out of curiosity, coincidentally releases such handle not to again interfere with it so long as the set continues to function.

Upon the tamperer who is looking for an opportunity to beat the coin detectors, the 105 effect is generally such discouragement because he reasons that he has broken the device and has lost the benefit derived by the spending of his money. Usually his tampering operations also will cease with the breaking of the circuit. The instant that improper influence upon the handle 75 is removed, said handle will revert to its normal position and the receiving circuit will be established. In 110 a few seconds, the time required for the elec- 115 120 125 130

trodes in the tubes to again become heated, the radio set will be heard, provided the clock mechanism has not, in the meantime, broken the receiving circuit through the movement of contact 64 from the contacts 57 and 61.

When a proper coin is placed in either of coin detector 28 or 29, such detector will be movable in a clockwise direction sufficiently far to discharge the coin therethrough. When such is the case, the member 80 will impinge upon an arcuate member 83 which is affixed to the main spring shaft 84 of the clock mechanism. Rotation to the extent which the coin detector may be moved imparts an arcuate movement to the member 83 whereby the main spring of the clock 85 is wound to operate the clock mechanism over the period of time which such mechanism should operate by reason of the position of the spring 66 upon the disc 73.

The clock mechanism illustrated which is shown as anchored upon the members 73 and 52 is that of the ordinary alarm clock with the substitution in place of the hair spring, of a weight 86 balanced upon the hair spring shaft whereby to insure an instant starting of the clock mechanism.

A full understanding of the clock mechanism can be had by an examination of the drawing, it not being believed that it is necessary to say more than that there is a plurality of gears intermediate the main spring shaft and the shaft for the weight 86 whereby the urging force of the main spring 85 is controlled over a period of time, so that a relatively small amount of energy stored in the spring 85 by its manual winding may be made to operate the clock mechanism herein illustrated over suitable periods of time.

When the disc 73 attached to the main spring shaft 84 shall have actuated the movable contact 64 in the circuit breaker, said disc 73 has permitted the travel of the clock mechanism the time limit prescribed therefor. The clock mechanism itself has sufficient force to continue to operate until shortly after the circuit is broken by the actuation of the member 64 when the clock mechanism is stopped by reason of resistance to the movement of its main shaft 84 obtained in the following manner.

For the purpose of regulating to a nicety the period of time which the clock movement may run after the circuit breaker disclosed in Figures 4 and 5 shall have been operated to terminate the flow of electromotive force to the radio tubes, an adjusting screw 87 is provided in the member 52. This is threaded therethrough with the head above the bracket 52 and with the threaded end of the shank in position to engage the arm 83 when the clock mechanism shall have operated a sufficient period that its main shaft 84 will have rotated through that angle

which actuates the circuit breaker. It is not objectionable to permit the clock to operate for a moment or a fraction of a moment after the circuit breaker has forced the discontinuance of the flow of electromotive force to the radio tubes in order to avoid the necessity for overly fine adjustments. 70

It is quite manifest that the turning of the clock shaft 84 as an incident to the impinging of the member 80 thereon need be over a 75 relatively small angle in order to attain either a five or ten minute or thirty minute playing period for the radio set. These extremes, one the minimum and the other the maximum, have been adopted as being consistent with 80 the ordinary demands of the average listener either in a hotel or in a public amusement place.

At the instant member 83 engages screw 87, the clock stops and cannot thereafter be 85 made to run until a coin detector 28 or 29 is actuated. Of course, there is an angle of movement of member 78 during which the lug 80 does not impinge member 83, this being that angle of movement necessary in coin detector 28 or 29 to determine whether a genuine coin or slug has been inserted therein. Until this angle is attained, member 80 cannot reach member 83.

In the operation of the present device, it 95 is presumed that the type of coin receiving mechanism will be such that there is a movement therein incidental to the deposit of the coin in the apparatus. The present device is not applicable to any mechanism which is 100 not capable of movement in connection with a deposit of a coin.

That type of coin detector shown in Figures 1, 6, 7, 8, 9, 11 and 12 is on the same order of that shown in the patent to A. D. Antoine 105 and C. C. Travis, numbered 1,372,666, dated March 29, 1921, and entitled "Check detector for coin actuated machines."

The coin is adapted to be received in a pocket 100 and conveyed in an arcuate path 110 by a carrier 101. The path of travel is in the direction shown in the arrow in Figure 9, the device being supplied with a plurality of means whereby slugs and blanks may be detected. As these latter comprise no part 115 of the invention, they are not described, it being essential only in the coin detector that when no coin is therein contained, there be sufficient play in the direction of the arrow whereby the contacts 42 and 49 may be separated. A stop means for preventing the rotation of the device in a counterclockwise direction beyond a fixed point hereinabove stated to be its normal position, is also required but such stops are common in all coin 125 detectors.

From an examination of the drawing and a reading of the description thereof to this point, the operation of the device should be clear. In order that there may be no mis- 130

understanding with respect to such operation, however, the following additional description is given.

- 5 The radio circuit with which the apparatus is employed may be any type of device but preferably powerline operated. The present apparatus is inserted into the circuit intermediate the source of power for the radio set and the radio circuit proper, and takes 10 the place of the manually operated switch which is generally found in radio sets. In the present device, there are two switches in connection with each coin detector, one normally open and the other normally closed. 15 The latter is opened as an incident to the movement of the handle of the coin detector. The other one may be closed through the agency of the coin detector when said coin detector shall have turned a predetermined 20 distance after the reception of a coin therein. The switch normally open is controlled from the main shaft of a clock mechanism, which clock mechanism is adapted to be wound as an incident to the engagement of 25 a member attached to the shaft of the coin detector when the coin detector shall have been actuated sufficiently far that it is determined that the item placed therein is a coin and not a slug. 30 The said switch which is normally open is connected to but insulated from the main shaft of the clock mechanism which is adapted to be actuated from the coin detector. When the coin detector shall have been rotated a sufficient distance, it rotates the clock main shaft so as to throw with a snap, a circuit breaker which comprises the normally open switch just referred to. 35 When the coin detector handle is released 40 and it returns to its normal position under the urge of the spring mechanism therein, the clock mechanism begins to move. The clock mechanism, instead of having a hair spring which sometimes necessitates agitating the movement in order to start the clock, is supplied with a counter-balance or weight bar whereby instant starting of the clock is secured. 45 The clock mechanism runs a predetermined 50 period of time, such time permitting of the clock main shaft to turn to that point where the spring thereon passes a dead center and causes its tension to separate the movable contact in the circuit breaker from the fixed 55 contact therein rather than to urge the continued engagement thereof. When this position is attained, by a snap motion, the circuit is instantly broken in such circuit breaker, the clock mechanism continuing to function for a few seconds longer and until the arcuate member upon the clock's main shaft which is engaged by a lug or roller member 60 upon the coin detector for winding the clock and closing the circuit breaker, impinges 65 upon a set screw, the position of which de-

termines the period over which the clock may run. This later is, of course, set in keeping with the desired operation of the circuit breaker, said circuit breaker being adjusted in respect to the time over which the radio circuit should operate in compensation for a specified coin deposited in one of the coin detectors.

At any time during the operation of the radio set that the coin detector handle is turned in a clockwise direction, the only possible direction from which it may be manipulated from its position of rest, there is a break through the normally closed switch in the apparatus whereby radio reception is shut off due to termination of the source of power.

Upon release of the coin detector handle, provided the clock mechanism has not run its prescribed time, electromotive force will again flow through the radio circuit and as soon as the tubes again shall have been heated to a sufficient degree of temperature to insure proper operation, program reception will resume.

Any other clock mechanism or system of parts which will cause the normally open switch to remain closed over a period of time may be substituted for the present clock mechanism, and any other coin detector wherein there is some play intermediate the time the coin is deposited therein and the winding of the clock or other actuating mechanism or the releasing thereof is begun may be substituted for that illustrated.

The many parts may take various forms, and different arrangements, all of which will be in keeping with the invention, the objects of which have been hereinabove fully outlined, and the subject matter of which is set forth in the appended claims.

It further should be quite manifest from an inspection of the drawings that the apparatus herein described is not limited to an application to a radio circuit, but may be employed upon any electrical circuit in which the time during which it is operative or active is to be regulated by coin control mechanism or its use is to be determined by clock mechanism or the equivalent thereof.

I claim:

1. The combination with an electrical circuit, of a main switch, timing mechanism for controlling said main switch, a coin detector for actuating said timing mechanism, and an ancillary switch adapted to be opened as an incident to the movement of said coin detector.

2. The combination with an electrical circuit, of a plurality of switches, one normally open and the other normally closed, a timing mechanism connected with said normally open switch, and a coin detector, movement of said coin detector being adapted to open said switch which is normally closed, and to

release said timing mechanism to close said normally open switch.

3. The combination with an electrical circuit, of a plurality of switches, one normally open and the other normally closed, a timing mechanism connected with said normally open switch, and a coin detector, movement of said coin detector being adapted to open said switch which is normally closed and to release said timing mechanism to close said normally open switch.

4. The combination with an electrical circuit, of a plurality of switches, one normally open and the other normally closed, a timing mechanism connected with said normally open switch, a coin detector, movement of said coin detector being adapted to open said switch which is normally closed and to release said timing mechanism to close said normally open switch, and means for stopping said clock mechanism when the selected period of operation thereof has expired.

5. The combination with an electrical circuit, of a main switch, a timing mechanism for actuating said switch, a coin detector for controlling said timing mechanism, and a spring-actuated switch normally closed and adapted to be released upon movement of said coin detector.

6. The combination with an electrical circuit, of a plurality of switches, a coin detector for controlling said switches, one of said switches being opened as an incident to any movement of said coin detector, the other of said switches being adapted to be closed coincidental with the movement of said coin detector when supplied with a proper coin.

7. The combination with an electrical circuit, of a plurality of switches, and a coin detector adapted to be moved in one direction and having means for retraction to its normal position, movement away from said normal position of said coin detector being adapted to open said circuit and maintain said circuit open until said coin detector shall have been returned to its normal position, said coin detector being adapted to close the other switch as an incident to advancement to the other extremity of its path of movement.

8. In an electrical circuit, coin-controlled switching means, said switching means providing means for closing said circuit as an incident to the deposit of a proper coin in said coin-controlling means and opening said circuit at any time when said coin-controlled means is manipulated.

9. The combination described in claim 8, and in which said coin detector has associated therewith a timing mechanism for determining the period over which said circuit shall be closed by the actuation of said coin detector.

10. The combination with an electrical circuit, of a circuit breaker, said circuit breaker including a movable member, a clock mecha-

nism connected to said movable member and having resilient connecting means adapted to urge said movable member into engagement with fixed contacts, movement beyond a predetermined point causing said resilient connection to urge a disconnection between said movable contact and said fixed contacts, and a coin detector having means for winding and releasing said clock mechanism, the winding of said clock mechanism being adapted to position said resilient connecting means to establish connection between said movable contact and said fixed contacts.

11. The combination with an electrical circuit, of a circuit breaker, said circuit breaker including a movable member, a clock mechanism connected to said movable member and having resilient connecting means adapted to urge said movable member into engagement with fixed contacts, movement beyond a predetermined point causing said resilient connection to urge a disconnection between said movable contact and said fixed contacts, a coin detector having means for winding and releasing said clock mechanism, the winding of said clock mechanism being adapted to position said resilient connecting means to establish connection between said movable contact and said fixed contacts, and means for stopping said clock mechanism when said resilient connecting means shall have broken the circuit established by said movable contact and said fixed contacts.

12. The combination with an electrical circuit, of a circuit breaker, said circuit breaker including a movable member, a clock mechanism flexibly connected to said movable member and having resilient connecting means adapted to urge said movable member into engagement with fixed contacts, movement beyond a predetermined point causing said resilient connection to urge a disconnection between said movable contact and said fixed contacts, a coin detector having means for winding of said clock mechanism being adapted to position said resilient connecting means to establish connection between said movable contact and said fixed contacts, and an ancillary switch adapted to break said circuit as an incident to movement of said coin detector from its position of rest.

13. A new article of manufacture comprising a clock mechanism, a switch resiliently connected thereto, a coin detector in association with said clock mechanism and having means for winding said clock mechanism and for releasing it for operation when a proper coin is deposited therein, means for stopping said clock mechanism when a predetermined timed operation thereof shall have been completed, said clock mechanism being adapted to open said switch anterior to the stopping of said clock mechanism, and an ancillary switch in said circuit for breaking said cir-

cuit coincident with a movement of said coin detector.

14. A switch mechanism for association with an electrical circuit comprising a coin detector, and a clock mechanism, there being a spring-actuated switch adapted to be opened by movement of said coin detector, and a main switch associated with said clock mechanism, movement of said coin detector beyond a predetermined point being adapted to wind said clock mechanism and to close said main switch, said main switch being opened by operation of said clock mechanism over a predetermined period of time,
- 15 and means for stopping said clock mechanism when said predetermined period of time shall have elapsed.
